(57) **CLAIM**

The ornamental designs for an “embedded USB hand controller,” as shown and described.

DESCRIPTION

FIG. 1 is a perspective view of the embedded USB hand controller;

FIG. 2 is a front view of the embedded USB hand controller;
FIG. 3 is a rear view of the embedded USB hand controller;
FIG. 4 is a left side view of the embedded USB hand controller;

FIG. 5 is a right side view of the embedded USB hand controller;

FIG. 6 is a top view of the embedded USB hand controller;
and,

FIG. 7 is a bottom view of the embedded USB hand controller.
